SEAT AND AISLE LIGHTING

Laurence W. Hiltman, Palos Heights, and George F. Gielow, Brookfield, Ill., assignors, by mesne assignments, to American Seating Company, a corporation of New Jersey

Application March 16, 1950, Serial No. 150,084

2 Claims. (Cl. 155—198)

1

This invention relates to seat and aisle lighting.

An object of the invention is to provide a structure for providing a bright illuminating light for the floor of the aisle in a vehicle while providing a subdued light above the seat and preferably illuminating a sign. Yet another object is to provide a structure in which a bright light is sheltered below an arm seat and well under the same so as to present no direct beams in a direction above the seat while at the same time directing a subdued light outwardly to a sign substantially flush with the outer surface of the seat to illuminate the sign and provide a subdued light for the upper portion of the aisle. Other specific objects and advantages will appear as the specification proceeds.

The invention is shown in an illustrative embodiment by the accompanying drawing, in which—

Figure 1 is a perspective view of a seat equipped with structure embodying our invention; Fig. 2, a perspective view of the sign plate and illuminating means therefor; and Fig. 3, a broken sectional view, the section being taken as indicated at line 3—3 of Fig. 1.

In the illustration given, 10 designates a seat structure adapted for busses, railways, aeroplanes, and other vehicles. The seat comprises base pedestals 11 upon which is mounted seat frame 12. The frame carries seat cushions 13 and back cushions 14. On the outer side of the seat 10 is an arm frame 15. Within the frame 15 there is provided a sign plate 16 formed of light-transmitting plastic or any suitable transparent material and provided on its rear with recesses 17 forming the sign indicia. The recesses may be covered with paint or lacquer to accentuate the sign characters or numerals and also the back side of the plate may be lacquered for a similar purpose. The sign may set out a name or seat number or other desired indicia.

We prefer to employ a plate 16 having a straight upper portion and an angular inwardly and downwardly inclined lower flange portion 18, as shown best in Fig. 3. The upper straight portion which bears the sign recesses 17 is aligned with a recess 19 in the outer plate of the arm rest frame so that the sign plate is visible from the outer side of the arm rest. A flange 20 is employed and preferably secured to the plate 21 of the arm rest frame 15, as shown best in Fig. 3.

At the base of the arm rest 15 and inwardly of the side plate 21, we provide an illumination box

22 having spaced ports 23 in the bottom thereof. In the illustration given, we provide three ports 23, and we prefer to employ above each port an electric lamp 24. The box 22 is provided along its top wall with spaced flanges 25 running longitudinally of the box and inclined upwardly and outwardly to receive the angular flange 18 of plate 16. With this structure, it will be noted that the box 22 and the aperture 23 are thus spaced well inwardly of the plate 21 so that the light rays from the bulb are shielded from persons walking along the aisle while, at the same time, the bulb rays are utilized for illuminating the sign above and giving a soft or reflected light visible to persons in the aisle. The name or number on the sign is set out prominently, but the light cast into the aisle from the sign is a subdued light. On the other hand, direct rays from the light bulb are cast upon the floor so that complete illumination of the floor is provided to enable the person in the aisle to see his way clearly and to avoid cases or any obstructions therein. The angularly-extending flange is effective in carrying the light rays to the sign portion above, while at the same time enabling the light bulb to be located at a point well inwardly of the outer edge of the arm rest so that the direct light rays from the bulb are shielded fully from the person in the aisle above.

30 In the drawing, three light bulbs are shown below the sign plate 16. It will be understood that a single light bulb or other source of illumination may extend lengthwise of the lower edge of the plate and the box 22 may be provided with spaced apertures 23 through which the rays from the single bulb may pass therethrough. If desired, the apertures 23 may be merged to form a single narrow slit or aperture.

35 While in the foregoing specification we have set out a specific structure in considerable detail for the purpose of illustrating the invention, it will be understood that the details of structure may be varied widely by those skilled in the art without departing from the spirit of our invention.

40 45 We claim:

1. In a seat structure having a base, a seat thereon, and an arm rest supported upon the side of the seat and terminating in a line generally aligned with the bottom portion of the seat, said arm rest having an opening therein, a light-transmitting sign-bearing plate closing said opening and forming a portion of the side wall of said arm rest, said plate having its lower edge terminating near the bottom of said arm rest, a casing secured to the lower edge portion

of said arm rest and providing an illumination box, said casing being slotted along its upper side to receive the lower edge of said light-transmitting plate, said casing having its lower side provided with an illumination opening for the projection of light rays below said arm rest, and a light bulb mounted in said illumination box for projecting rays downwardly below said arm rest and upwardly through the plate forming a panel in said arm rest.

2. In a seat structure having a base, a seat thereon, and an arm rest supported upon the side of the seat and terminating in a line generally aligned with the bottom portion of the seat, said arm rest having an opening therein, a light-transmitting plate closing said opening and forming a portion of the side wall of said arm rest, said plate having its lower edge terminating near the bottom of said arm rest, a casing secured to the lower edge portion of said arm rest and providing an illumination box, said casing being slotted along its upper side to receive the lower edge of said light-transmitting plate, said casing having its lower side provided

5 with an illumination opening for the projection of light rays below said arm rest, and a light bulb mounted in said illuminating box for projecting rays downwardly below said arm rest and upwardly through the plate forming a panel in said arm rest.

LAURENCE W. HILTMAN.
